COLLAPSIBLE GATE

Roscoe I. Nightingale, Phoenix, Ariz.

Application January 7, 1946, Serial No. 639,580

3 Claims. (Cl. 160—161)

1

The present invention relates to an improved foldable or collapsible fence such as serves as a temporary gate.

More particularly, the invention appertains to a lattice-like gate, the latter being foldable and being so designed and specifically constructed as to function as a guard for an open doorway, whereby to provide a simple and practical device such as may be temporarily placed in the doorway, this in a manner to prevent small children from passing from one room to another through said thus guarded doorway.

In carrying out the principles of the invention I thus provide a foldable doorway gate, the same characterized by overlapping pivotally connected bars or slats and certain of said slats, being provided on their outer ends with especially constructed adapters, the latter being so made as to frictionally grip portions of the door frame, this in a manner to satisfactorily hold the gate, as a unit, in place.

Another object of the invention is to provide a safety gate of the aforementioned type in which the so-called adapters are in the form of rubber or equivalently padded forks said forks serving to straddle those surfaces of the door frame with which they directly coat.

Other objects, features and advantages of the invention will become more readily apparent from the following description and the accompanying illustrative drawings.

In the drawings, wherein like numerals are employed to designate like parts throughout the views:

Figure 1 is an elevational view showing an open doorway and also showing the improved safety gate positioned therein and ready for use.

Figure 2 is an enlarged fragmentary view which may be said to be taken on approximately on the line 2—2 of Figure 1.

Figure 3 is a view partly in section and partly in elevation showing an outer end of one of the bars or slats, the same equipped with the aforementioned adapter or fork.

Figure 4 is an end view of the structure seen in Figure 3.

Figure 5 is a view similar to Figure 3 showing a different style of adapter, this an all rubber type.

Figure 6 is an end view of the type or style of adapter seen in Figure 5.

Referring now to the drawings by distinguishing reference characters A designates a door frame or an open doorway in a wall construction B. The improved safety gate is fitted temporarily

and removably in the lower half portion of the doorway and is detachably mounted on the door frame, said gate being denoted, generally speaking, by the numeral 10. Looking at the gate as an overall unit it is of open-work or lattice-like form. It is therefore of the shape and the general appearances illustrated in the drawings. It is made up of a plurality of slats or bars interconnected and pivotally connected as shown.

10 The upper pair of downwardly converging slats are denoted by the numerals 11 and the slats of the lower pair are denoted by the numerals 12. The intermediate or body slats are differentiated and denoted by the numerals 13.

15 The assembling and hinging connection for the various slats are denoted by the numerals 14. Specifically, these connectors are in the form of headed pins as shown in Figure 2, said pins being indicated by the said numeral 14 and the pins axially extend through thickened portions

15 of the adjacent interconnected and overlapping slats. Washers 16 are on these pins and interposed between the portions 15 keeping said portions in spaced apart relationship and providing 20 the desired clearances. Additional washers 17 are provided on opposite headed ends of the pivot pins to render the connection also freely

25 operable. The major portions of the slats, the portions 18 ranging between the hinging portions 15 are relatively thin. The slats are so constructed and interconnected as to render same 30 freely expansible and contractible for compactness, convenience and folding. There is also less chance of small tots pinching fingers between the slats when they are constructed as

35 herein shown and described.

The adapters are denoted, as general units, by the numerals 19 in Figure 3 and 19a in Figures 5 and 6. In either instance each adapter is in the

40 form of a fork whose fingers are fork-ends straddle the coacting stops in the door frame construction. The adapter 19 in Figure 3 comprises a pair of arms having inner ends 20 pinned or otherwise secured in place as at 21. The outer ends of the arms project and curve properly as indicated at 22 and these ends are fashioned to accommodate semi-spherical tips or buffers 23, the latter of rubber or equivalent material.

The adapters of Figures 5 and 6 are also in 45 the form of suitably proportioned forks but are each made of one piece of rubber. This includes a socket 24 fitted over the slat ends, said socket carrying retaining fingers or fork arms 25.

It is to be noted, in passing, that the inner ends 50 of the respective slats 12, 11 are suitably marked

as by coloring and as indicated at the point 26, these coacting to denote the "upper" end of said gate.

It is to be noted that there are, in the simple embodiment of the invention shown in the drawings, four distinguishable slat units; namely, A, B, C and D which go to make up the complete gate. Unit A comprises a pair of duplicate relatively long slats 12-12 and these are centrally overlapped and hingedly connected to one another to provide upper and lower diverging end portions and to define a so-called X-shaped slat unit. The lower diverging ends, the ends closest to the floor, are provided with the aforementioned cushioned adapters or grips and these grips, when in place, support the major portion of the weight of the entire gate. The uppermost inverted U-shaped unit B comprises a pair of slats 11-11 which are conveniently differentiated as secondary slats and these slats have their outer ends provided with corresponding adapters 24 which bind against the door frame and suspend a part of the weight, but are, primarily, retainers to prevent the gate from being pushed and thus displaced from the doorway frame. In connection with the secondary slats 11-11, it is to be noted that the hinge connection between the inner ends is inwardly of the tips of said ends, thereby permitting said tip portions to project beyond the hinge connection. It is these projecting tips or ends which are marked to denote the upper side of the gate and to facilitate properly lodging the gate in a doorway frame. There is a second V-shaped slat unit C comprising a pair of duplicate slats 14-14 also shorter than the slats 12-12 in said X-shaped unit A and of lengths corresponding to the slats 11-11 in said inverted V-shaped slat unit B. Said slats 14-14 have their inward ends slightly overlapped and hingedly connected together and have their intermediate portions crossing and hinged to the respective intermediate portions of the diverging lower end portions of the slats 12-12 of the X-shaped unit A. The remaining additional slats 13-13 have their intermediate portions overlapped and hingedly connected with each other to define the remaining slat unit D called the second X-shaped unit. The lower diverging end portions of slats 13 are hingedly connected to the intermediate upper end portions of slats 12 and the extreme lower ends of slats 13 are hingedly connected to the upper ends of the slats 14-14 in unit C. Finally, the upper ends of the slats 13-13 are hingedly connected to the intermediate portions of slats 11-11. The upper grips are only on the outer ends of the slats 11-11 while the remaining grips are on the lower ends only of the slats 12-12. It will be noted that these lower ends of slats 12-12 and the outer ends of slats 11-11 are directly above each other when the gate is in use, as shown in Figure 1, and actually project to positions beyond the outer ends of the additional slats in units C and D. Consequently, the outer ends of the slats C and D are spaced inwardly and are clear of contact with the door frame. This means, therefore, that the gate as a unit has four-point engagement with the coacting portions of the door frame.

The invention, as is now evident, is an easily placed and removed gate to be used in the home and other places to keep small children and pets from passing from one room to another while at the same time leaving the door (not shown) open.

When one wishes to use the gate they simply open it up and set it in the doorway. The rubber

tipped feet or forks are so shaped that they will fit on each side of the door stops, thus holding the gate securely in place. When not in use the gate folds up into a compact form. The rubber tips of the feet prevent the gate from marring the finish of doorways.

Changes in shape, size, materials and rearrangement of details and parts may be resorted to in actual practice, so long as they do not depart from the spirit of the invention or the scope of the appended claims, as is well understood.

I claim:

- 15 1. A foldable, readily applicable and removable fence adapted to be removably placed across an open doorway frame and usable as a safety gate comprising an X-shaped slat unit made up of a pair of duplicate relatively long slats, said slats being overlapped at their central portions and hingedly connected to each other, the lower diverging ends of said slats being provided with adapters, said adapters having outstanding cushioned arms adapted to straddle and releasably grip a portion of the doorway frame, a second slat unit, said second unit being of inverted V-shaped form, the outer ends of the slats being foldably connected to the upper diverging end portions of the slats of said X-shaped unit and being provided with outstanding spaced adapters, 20 said adapters also having cushioned arms which are adapted to straddle coacting portions of the stated doorway frame, the inner adjacent ends of the slats of said inverted V-shaped unit being overlapped and crossing each other and hingedly connected together with the extremities projecting slightly beyond the latter hinged connection, said extensions being adapted to distinguish the "upper" portion of the gate from the "lower" portion and to thus facilitate the step of placing the gate in position for use and subsequently removing it, and a plurality of additional slats hingedly and foldably connected with one another and collectively mounted on the adjacent slats of the stated X-shaped and V-shaped units, 25 the outer ends of the slats in said V-shaped unit and the lower ends of the slats in said X-shaped unit being adapted to occupy portions directly above one another but spaced outwardly from the corresponding ends of said additional slats.
- 30 2. The structure defined in claim 1, wherein the major portions of each slat are relatively thin and restricted in cross-section and corresponding minor portions of the slats are comparatively thick, the thick portions of respectively coacting slats being aligned, overlapped and hingedly connected, and the thin portions being spaced from each other to prevent direct wiping contact of said thin portions, whereby to prevent face-to-face scissors-like shearing and to minimize finger pinching during spreading and folding stages of the over-all slats.
- 35 3. A foldable, readily applicable and removable fence adapted to be removably placed across an open doorway frame and usable as a safety gate comprising an X-shaped slat unit made up of a pair of duplicate relatively long slats, said slats being overlapped at their central portions and hingedly connected to each other, the lower diverging ends of said slats being provided with adapters, said adapters having outstanding cushioned arms adapted to straddle and releasably grip a portion of the doorway frame, a second slat unit, said second unit being of inverted V-shaped form, the outer ends of the slats being foldably connected to the upper diverging end

- 40 45 50 55 60 65 70 75 80 85 90 95

portions of the slats of said X-shaped unit and being provided with outstanding spaced adapters, said adapters also having cushioned arms which are adapted to straddle coacting portions of the stated doorway frame, the inner adjacent ends of the slats of said inverted V-shaped unit being overlapped and crossing each other and hingedly connected together with the extremities projecting slightly beyond the latter hinged connection, said extensions being adapted to distinguish the "upper" portion of the gate from the "lower" portion and to thus facilitate the step of placing the gate in position for use and subsequently removing it, a second V-shaped slat unit comprising a pair of duplicate slats also shorter than the slats in said X-shaped unit and of lengths corresponding to the slats in said inverted V-shaped slat unit, the slats in said second V-shaped slat unit having their inward ends slightly overlapped and hingedly connected, having their intermediate portions crossing and hinged to the respective intermediate portions of the diverging lower end portions of the slats of the X-shaped unit, and additional slats hinged at their lower ends to the upper ends of the slats in said second V-shaped unit and

having their upper ends operatively connected with the slats of the inverted V-shaped unit, said additional slats having intermediate portions overlapped and hingedly joined and providing a second X-shaped unit and also having said intermediate portions crossing and hingedly connected with intermediate portions of the upper diverging end portions of the respective slats of said first-named X-shaped unit, the outer ends of the slats in said second V-shaped unit and second X-shaped unit being spaced inwardly of the outer ends of the slats of the inverted V-shaped unit and the lower ends of the slats of the first-mentioned X-shaped unit.
